UNITED STATES PATENT OFFICE.

OSCAR C. MILLER, OF PHILADELPHIA, PENNSYLVANIA, ASSIGNEE OF ONE-HALF TO
CYRIL M. GIDLEY, OF PHILADELPHIA, PENNSYLVANIA.

SPARK-PLUG.

1,225,467.

Specification of Letters Patent.

Patented May 3, 1917.

Application filed July 21, 1914. Serial No. 352,221.

To all whom it may concern:

Be it known that I, OSCAR C. MILLER, a citizen of the United States, residing at Roxborough, Philadelphia, in the county of 5 Philadelphia and State of Pennsylvania, have invented new and useful Improvements in Spark-Plugs, of which the following is a specification.

This invention relates to improvements in 10 spark plugs for internal combustion engines and the like.

In carrying out the present invention, it is my purpose to improve and simplify the general construction of spark plugs and to 15 provide a plug wherein one electrode may be adjusted relatively to the other so as to vary the length of the spark gap.

With the above and other objects in view, the invention consists in the construction, 20 combination and arrangement of parts hereinafter set forth in and falling within the scope of the claim.

In the accompanying drawing;

Figure 1 is a view in side elevation of a 25 spark plug constructed in accordance with the present invention.

Fig. 2 is a longitudinal sectional view therethrough.

Fig. 3 is a cross sectional view on the line 30 3-3 of Fig. 2.

Fig. 4 is a similar view on the line 4-4 of Fig. 2.

Fig. 5 is a bottom plan view.

Fig. 5^a is a cross sectional view through a 35 modified form of electrode.

Referring now to the drawing in detail, 1 designates a metallic shell forming the ground electrode of the plug and having one end threaded exteriorly as at 2 to engage 40 the opening in the cylinder wall and the opposite end threaded exteriorly as at 3. The outer surface of the central portion of the shell or casing 1 is preferably polygonal in cross section so as to receive a wrench or 45 similar tool whereby the plug may be screwed into the opening in the cylinder. The interior of the shell 1 at the cylinder end thereof is formed with a small bore 4 and the remaining end portion of the shell 50 forms a relatively large bore 5 and at the junction of the bores 4 and 5 is a shoulder 6 against which seats a packing ring 7. 8 designates an electrode holder formed of porcelain or similar insulating material and 55 disposed within the shell 1. One end portion

of the electrode holder 8 is relatively small in diameter as compared with the remaining portion thereof and such small portion fits within the small bore 4 of the shell, while the large diameter of the holder fits within 60 the bore 5 of the shell and at the junction of the small and large portions of the electrode holder is a shoulder 9 resting against the packing ring 7 and serving to hold the electrode holder within the shell in proper position. Formed in the holder 8 centrally thereof is a longitudinal bore 10, while formed on the outer end of the electrode holder, that is the end remote from the cylinder wall, is an outwardly projecting nipple 11 coaxial with the bore 10 and terminating short of the adjacent extremity of the casing or shell 1. 12 designates a circular block disposed within the outer end of the shell 1 and having a recess formed in 65 the inner face thereof receiving the nipple 11 on the adjacent end of the holder 8 and formed integral with the block 12 and projecting outwardly therefrom is a boss 13 formed with a longitudinal bore 14 alining 70 axially with the bore in the electrode holder 8. Threaded onto the outer end of the shell 1 is an annulus 15 formed with an inwardly extending flange 16 engaging the shoulder 17 formed at the juncture of the block 12 with the boss 13, such flange coacting with the shoulder 7 to hold the electrode holder 8 within the shell and prevent accidental movement thereof. The outer surface of the annulus 16 is preferably polygonal in 75 cross section so that the annulus may be threaded onto the adjacent end of the shell by means of a wrench or similar tool. One end portion of the bore 10 in the electrode holder 8 is non-circular in cross section and disposed within such non-circular portion and of a cross sectional configuration corresponding thereto is a nut 17. Passed through the axially alining bores 10 and 14 80 and threadedly engaging the nut 17 is a stem 18 forming the power electrode of the plug and having the lower end thereof beyond the cylinder extremity of the shell 85 equipped with an annular disk 19 and the opposite end screw threaded and projecting beyond the boss 14. The disk 19 is of a diameter approximately equal to the interior diameter of the shell at the cylinder end of the latter and is spaced apart from the end of the shell to form the spark gap. 90

105

110

By means of this construction, it will be seen that the disk acts as a deflector to break the passage of the products of combustion into the shell of the plug when the gaseous mixture is exploded, thereby prolonging the life of the plug and preventing mutilation of the inner end of the electrode holder 5 in the use of the plug. Threaded onto the last-mentioned end of the stem 18 is a lock nut 20 and interposed between the confronting surfaces of the lock nut 20 and the boss 14 are washers 21, while disposed between the washers 21 is a binding spring 22 acting to hold the lock nut against accidental turning movement on the stem. When it is desired to vary the distance between the disk 19 and the adjacent end of the shell 1 or power electrode so that the length of the spark gap may be changed, the nut 20 is loosened and the stem 18 rotated within the nut 17. In the rotation of the stem the latter moves longitudinally incident to the threaded connection between the same and the nut 17 and when the desired adjustment has been attained the lock nut 20 is tightened so as to hold the power electrode against movement.

If desired, the periphery of the disk 19 may be serrated as shown in Fig. 5^a so as to insure the segregating of the sparks jumping across the gap.

It will be seen that I have provided a spark plug wherein the power electrode may be adjusted relatively to the ground electrode so as to vary the length of the spark gap and wherein the component parts are so correlated and arranged as to reduce the

possibility of derangement to a minimum and enable the spark plug to be readily assembled and dismantled.

I claim:

In a device of the kind described, in combination a metallic shell, having a transverse inner annular shoulder, a packing engaging said shoulder, an electrode holder disposed in said shell and having a shoulder seated on said packing, and formed with an unthreaded polygonal bore and with an elongated unthreaded opening of lesser diameter than said boss, a circular block formed terminally of said shell, a boss formed with a cavity in which said block fits, said bore having its lower portion formed of a uniform diameter with said electrode holder and its upper portion reduced to form a shoulder, a cap threaded on said shell and pressing the shoulder of said boss to hold the boss and holder in engagement, a stem screw threaded throughout its main length and adapted to pass loosely through the bore and opening of said electrode holder but threaded into said boss, an annular disk formed at one end of said stem, a nut fitted simply in said polygonal bore, said stem being threaded into said nut, and a lock nut engaging the free end of said stem, said disk disposed outside of said shell.

In testimony whereof I affix my signature in presence of two witnesses.

OSCAR C. MILLER.
